G. A. BERRY

SASH LOCK

Filed Aug. 13, 1923

Patented Oct. 28, 1924.

1,513,308

UNITED STATES PATENT OFFICE.

GEORGE A. BERRY, OF MODESTO, CALIFORNIA.

SASH LOCK.

Application filed August 13, 1923. Serial No. 657,141.

To all whom it may concern:

Be it known that I, GEORGE A. BERRY, a citizen of the United States, and a resident of Modesto, county of Stanislaus, State of California, have invented a new and useful Sash Lock, of which the following is a specification.

This invention relates to sash locks and has for its primary object the provision of a simple and inexpensive device of this character which may be conveniently and quickly applied to a sliding sash of usual construction which will include novel means to engage with the sash guide of a window frame or casing, to coact therewith and hold the sash in a locked position of adjustment, and in such manner that will render it exceedingly difficult, if not impossible, to open the sash from the outside.

Another object of the invention is to provide a lock of this character which can be adjusted with dispatch as the occasion requires, and which will include a movable bolt and means for yieldingly holding same in any intended position of adjustment and in a manner to prevent undue rattling of the parts under the action of wind.

My invention, therefore, comprises certain new features of construction and arrangement and combination of elements hereinafter set forth and pointed out in the claims annexed hereto.

In the drawings:

Figure 1 is a front elevation of a portion of a sliding sash and a window frame showing the application of my invention thereto;

Figure 2 is a horizontal section on line 2-2 of Figure 1;

Figure 3 is a perspective view of the guide plate;

Figure 4 is a perspective view of the latch or keeper element;

Figure 5 is a plan view of the sliding bolt;

Figure 6 is a side view of the bolt; and

Figure 7 is a perspective view of the spring.

In carrying the invention into practice use is made of a sliding sash (5) of usual well known construction, the same mounted to slide vertically in the guide (6) of a window frame (7). The inner bar of the guide groove (6) is formed with a vertical series of recesses (8) which may be suitably spaced apart. Adapted to register with any one of these recesses is an opening (9)

formed in the side rail of the sliding sash.

Mounted to slide in the opening (9) is a bolt (10) having a cylindrical end (11) adapted to be projected into any one of the aforesaid recesses (8) and to hold the sash (5) in a definite or fixed position of adjustment. This bolt is also slidable in an opening (12) of the guide plate (13) which is secured by fastenings (14) to the side rail of the sash (5) as clearly shown in Figures 1 and 2 of the drawings. Mounted upon the guide plate (13) so as to traverse the opening (12) at one side of the center thereof is a keeper bar or strip (14), the purpose of which will be referred to hereinafter.

The bolt (11) is formed on its opposite sides with grooves (15-15). At one side the bolt is recessed or cut away at (16) so as to form a tapered nose (17) over which may be extended the loop or bight (18) of a substantially V shaped spring (19). This spring is formed of a single piece of wire which inherently persuades lateral separation from one another of the legs (20).

These legs are accommodated in grooves (15-15) of the bolt and they are extended through the opening (12) of the guide plate (13) so as to yieldingly engage therewith at diametrically opposite points of the opening (12). At a point outwardly of the opening the legs (20) of the spring are formed into manipulating loops (21) and same are located respectively at the opposite sides of a manipulating lip (22) on the outer end of said bolt. In this manner it is manifest that when the bolt is adjusted to any one of its respective positions it is yieldingly held against casual movement away from this position.

This is due to the fact that the legs (20) of the spring bar are held with sufficient yielding force against the diametrically opposite points of the opening (12) to create friction between the parts. When it is desired to free the bolt in order that it can be moved in its opening (9) the manipulating loops (21) are grasped between the fingers of the hand and brought together toward the lip (22) of the bolt. The legs (20) are then moved out of frictional engagement with the walls of the opening (12). The spring is so designed that maximum adjustment of the bolt may be made in either direction and the bolt may be satisfactorily held in its intended position of adjustment.

When the bolt is moved to the dotted line

position shown in Figure 1 the sash (5) may be raised or lowered and the opening (9) brought into registration with a selected recess (8). The bolt is then moved to the full line position shown in Figure 1 in order that its cylindrical end (11) will be seated in said recess (8). The sash is now secured in its adjusted position. It shall be understood that the bolt may be applied to either the upper or lower sash. If desired both sashes may be equipped with my invention.

In order to prevent accidental or full withdrawal of the bolt from the opening (9) I provide same with a recess (23) which accommodates the plate or keeper (14). The wall (24) of the recess constitutes a stop to coact with said plate or keeper (14) when the bolt is withdrawn to the limit of its outward movement. Aside from functioning in this manner the bolt is held against rotation so as to hold the loops (21) of the spring (19) always in superposed positions and substantially parallel to the horizontal lip (22). The purpose of this dual functioning of the parts is to always expose the loops (21) where they may be conveniently grasped between the fingers of the hand and manipulated as desired.

I claim:

1. A sash lock comprising a sliding bolt adapted to be mounted in the side rail of a sash and to be projected into the guide groove of a window frame, a plate having an aperture through which said bolt is free to work and to slide with relation to said groove, means on the bolt coacting with the plate to hold the former against displacement from the sash, and spring means carried by the bolt and coacting with the walls of the aperture of said plate to hold the bolt in its positions of adjustment with respect to said groove.

2. A sash lock comprising a sliding bolt adapted to be mounted in the side rail of a sash and to be projected into the guide groove of a window frame, a plate having an aperture through which said bolt is free to work and to slide with relation to said groove, means on the bolt coacting with the plate to hold the former against displacement from the sash, and spring means carried by the bolt and coacting with the walls of the aperture of said plate to hold the bolt in its positions of adjustment with respect to said groove, and manipulating portions formed on the spring and exposed from one side of said plate.

3. A sash lock comprising a sliding bolt adapted to be mounted in the side rail of a sash and to be projected into the guide groove of a window frame, a plate through which said bolt is free to work and to slide

with relation to said groove, means on the bolt coacting with the plate to hold the former against displacement from the sash, and spring means carried by the bolt and coacting with said plate to hold the former in its positions of adjustment with respect to said groove, and manipulating portions formed on the spring and exposed from one side of said plate, said spring formed of a single length of wire having relatively separable branches normally tending to move apart from one another and yieldingly engage with said plate.

4. A sash lock comprising a sliding bolt adapted to be mounted in the side rail of a sash and to be projected into the guide groove of a window frame, a plate through which said bolt is free to work and to slide with relation to said groove, means on the bolt coacting with the plate to hold the former against displacement from the sash, and spring means carried by the bolt and coacting with said plate to hold the former in its position for adjustment with respect to said groove, and manipulating portions formed on the spring and exposed from one side of said plate, said spring formed of a single length of wire having relatively separable branches normally tending to move apart from one another and yieldingly engage with said plate, the bolt having longitudinal grooves in which said relatively separable branches are operatively accommodated.

5. A sash lock comprising a sliding bolt adapted to be supported in the side rail of a sliding sash and to coact with the guide groove of a window frame to hold the sash against sliding movement, aperture means adapted to be fixed on the sash, and means carried by the bolt and yieldingly engaging with the walls of the sash means to hold the bolt in its respective positions of adjustment.

6. A sash lock comprising a sliding bolt adapted to be supported in the side rail of a sliding sash and to coact with the guide groove of a window frame to hold the sash against sliding movement, means adapted to be fixed on the sash, and means carried by the bolt and yieldingly engaging with the sash means to hold the bolt in its respective positions of adjustment, and including a spring formed of a single piece of wire bent on itself and extending in the length of the bolt so as to provide a pair of clamps which are freely slideable through said means on the sash and which are terminally formed with manipulating extremities adapted to be pressed together to release said clamps from said sash means.

GEORGE A. BERRY.
